[57] CLAIM

The ornamental design for a package of containers, as shown and described.

DESCRIPTION

FIG. 1 is a perspective view of a package of containers showing my new design;

FIG. 2 is a bottom plan view thereof;

FIG. 3 is a rear side elevation thereof, the front elevation being a mirror image;

FIG. 4 is a top plan view thereof; and

FIG. 5 is a right side elevation thereof, the left side elevation being a mirror image.
